UNITED STATES PATENT OFFICE.

JOHN D. GLADWIN, OF NEWARK, NEW JERSEY, ASSIGNOR TO THE STANDARD MACHINE BRUSH COMPANY, A CORPORATION OF NEW JERSEY.

BRUSH-MAKING MACHINE.

1,359,165.

Specification of Letters Patent. Patented Nov. 16, 1920.

Application filed June 21, 1918. Serial No. 241,112.

To all whom it may concern:

Be it known that I, JOHN D. GLADWIN, a citizen of the United States, residing at Newark, in the county of Essex and State 5 of New Jersey, have invented certain new and useful Improvements in Brush-Making Machines; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15

The present invention has reference, generally, to brush making machinery; and the invention relates, more particularly, to an improved construction of machine for 20 bunching the bristle material, cutting and forming fastening staples, and then inserting the bunched bristles together with a fastening staple into the brush back, with said staple serving to secure the bunched 25 bristles to the brush back.

The invention has for its principal object to provide a very simple automatic machine, which is arranged and constructed to automatically feed staple wire to a novel cutting 30 and forming means, and then pick up and feed, in coöperating relation with the formed staple, a bunch of bristles, and finally to automatically attach the staple and bristles in secured relation to a brush 35 back; the machine being properly timed to perform its several functions in proper sequence, and in a very simple and efficient manner.

Other objects of the present invention, 40 not at this time more particularly enumerated, will be clearly understood from the following detailed description of the same.

With the various objects of the present invention in view, the same consists, primarily, in the novel construction of brush 45 manufacturing machine hereinafter set forth; and the invention consists, furthermore, in the novel arrangements and combinations of the various devices and parts, 50 as well as in the details of the construction of the same, all of which will be herein-after more fully described in the following specification, and then finally embodied in the claims appended thereto.

The invention is clearly illustrated in the 55 accompanying drawings, in which:—

Figure 1 is a front elevation of the novel mechanism for brush making embodying the principles of my present invention.

Fig. 2 is a sectional plan view of the 60 transmission mechanism for operating the brush making elements of the machine, taken on line 2—2 in said Fig. 1.

Fig. 3 is an enlarged detail front elevation of the head carrying the brush making 65 elements.

Fig. 4 is a detail face view of the bristle bunching and feeding elements in operation.

Fig. 5 is a detail plan or top view of said head carrying the brush making elements, 70 portions being broken away, and the feed plunger mechanism being removed.

Fig. 6 is a transverse section taken on line 6—6 in said Fig. 5, the feed plunger mechanism being shown in this view. 75

Similar characters of reference are employed in all of the above described views, to indicate corresponding parts.

Referring now to said drawings, the reference character 1 indicates the complete 80 brush making mechanism, the same comprising a suitable frame-work or supporting structure 2 (indicated by dot and dash lines in said Fig. 1), to which is secured, in desired location, and by any suitable means, 85 a head bracket 3, upon which the brush making elements are mounted.

Formed in said head bracket 3 is a vertical channeled guideway 4, in which is slidably mounted a slide block 5, adapted 90 to be reciprocated up and down in said guideway. Secured upon said slide block 5 is a staple cutting and forming die 6.

Connected with said frame-work or supporting structure 2 is a vertical channeled 95 guide member 7, in which is slidably mounted, to be reciprocated up and down therein, a cross-head 8. Said cross-head 8 is provided with a socket-means 9, adjacent to its outer end, in which is secured 100 the upper end of a plunger rod 10. Said staple cutting and forming die 6 is provided with a vertical guide opening 11, through which said plunger rod 10 extends.

Connected with said head bracket 3, to 105 the right of said guideway 4, are a pair of stationary wire guides 12, adapted to guide staple wire 13 fed therethrough beneath

said cutting and forming die 6, when the latter is raised or withdrawn to normal initial position. Arranged between said wire guides 12 are a pair of pivoted spring 5 pressed gripping dogs 14, one above and one below the wire 13, and so disposed as to grip the wire between their co-operating toothed free ends 15 to prevent retractive movement of said wire 13, while freely 10 yielding to any forward or feeding movement of said wire.

Connected with the outer end of said head bracket 3 is a horizontal channeled guide portion 16, in which is mounted so as to be 15 capable of back and forth movement therein, a slide member 17. Secured to said slide member 17, so as to project laterally therefrom in alignment with said stationary wire guides 12, are a pair of spaced wire supporting blocks 18, perforated laterally to 20 permit the passage of staple wire therethrough. Arranged between said wire supporting blocks 18, and in supported connection with said slide member 17, are a pair of pivoted spring pressed feeding dogs 19, one above and one below the wire 13, and so disposed as to grip the wire between their co-operating toothed free ends 20, when the slide member 17 moves forward, to thereby 25 propel the wire forward through said wire guides 12 to proper position beneath said staple cutting and forming die 6, but yielding to slide freely backward over the said wire when said slide member is retracted.

30 The means for reciprocating said slide member 17, and the wire feeding means carried thereby, comprises a lever 21 pivoted to a fulcrum stud 22 arranged in connection with the frame-work or supporting structure 2. The lower end of said lever 21 is pivotally connected with the slide member 17. The upper end of said lever 21 is provided with a cam portion 23. Connected 35 with the side of said cross-head 8 is an outwardly projecting arm 24, having at its free end a stud 25 which engages said cam portion 23 of the lever 21. Secured to the outer end of said guide portion 16 is a tail piece 26 provided at its outer end with an upwardly extending stop abutment 27. Connected with the outer end of said slide member 17 is an adjustable stop-means 28 which engages said stop abutment 27 to determine the retracted and normal initial position of 40 said slide member 17 and the wire feeding means carried thereby. A spring means 29 interconnected between said slide member 17 and said stop abutment 27 serves to retract the former, and the wire 45 feeding means carried thereby, to normal initial position after operation. As the cross-head 8 rises to retract the plunger rod 10 after its operation, the stud 25 moves upwardly therewith into engagement 50 with the cam-portion 23 of the lever 21

swinging its upper end outward and thereby its inner end inward to slide inwardly the slide member 17, and the wire feeding means carried thereby, so as to feed beneath the staple cutting and forming die 6 a fresh 70 portion of wire ready to be operated upon. When the cross-head 8 moves downward the cam-portion 23 of the lever 21 is released from engagement by the stud 25, so that the spring means 29 may retract the slide 75 member 17, and consequently return the lever 21 to normal initial position.

80 Mounted to reciprocate transversely upon said head bracket 3, and adapted to pass through an opening 30 provided in the lower end of said channeled guideway 4, so as to be projected beneath said staple cutting and forming die 6, is an anvil member 31 over which the wire 13 is fed preparatory to cutting and forming the same into a staple. The means for reciprocating said anvil member 31 comprises a lever 32 pivoted to a fulcrum bracket 33 arranged in connection with the frame-work or supporting structure 2. The lower end of said lever 32 is pivotally connected with the inner end of said anvil member 31. The upper end of said lever 32 is provided with a cam-portion 34. Connected with the body of said cross-head 8 is an outwardly projecting stud 35 which engages said cam portion 34 of the lever 32. A spring means 36 interconnected between the lower end or arm of said lever 32 and said frame-work or supporting structure 2 serves to retract said lever and the 100 anvil member connected therewith to inoperative position. As the cross-head 8 rises to retract the plunger rod 10 after its operation, the stud 35 moves upwardly therewith into engagement with the cam portion 34 of 105 said lever 32 swinging the upper end of said lever back to slide out said anvil member 31 to operative position.

110 One means for producing the reciprocation of the cross-head 8, and consequently also producing the timed operation of the wire feeding mechanism and the operation of the anvil member, is illustrated more particularly in Figs. 1 and 2. Suitably mounted in connection with the frame-work or 115 supporting structure 2 is a driving shaft 37 having a driving pulley 38 fixed thereon, over which runs a driving belt 39, operated from any suitable source of power, such, for example, as an electric motor 40. Fixed on 120 said shaft is a female clutch member 41. Mounted on said shaft 37 is a hollow shaft or sleeve 42, upon which is splined a movable or shiftable male clutch member 43, capable of being moved into coupled relation to said female clutch member 41, so that the rotation of said driving shaft 37 125 may be imparted to said hollow shaft or sleeve 42. Fixed on said hollow shaft or sleeve 42 is a spur gear 44. Also mounted 130

in connection with said frame-work or supporting structure 2 is a lay shaft 45, provided with a gear 46 which meshes with and is driven by said spur gear 44. In like manner, there is provided a counter shaft 47 and a counter shaft 48, which are provided with the respective gears 49 and 50, driven by a gear 51 connected with said lay shaft 45. Driven by said countershaft 47 is a crank-member 52. Mounted upon said frame-work or supporting structure 2 is a fulcrum block 53 upon which is pivoted a rocking lever 54, one end of which is operatively connected with said cross-head 8 by a link 55, and the other end of which is operatively connected with said crank-member 52 by a connecting rod 56. The rotating of said shaft 47 and the crank-member 52 oscillates said rocking-lever 54, which in turn produces a properly timed reciprocation of said cross-head 8, and the mechanism operated therefrom.

The means for effecting a properly timed reciprocation of said slide block 5, and the staple cutting and forming die 6 carried thereby, comprises a bracket bearing 57 associated with said head bracket 3, in which is journaled a fulcrum shaft 58. Secured upon one end of said fulcrum shaft 58 is a lever arm 59, having at its free end a transverse stud 60 operatively engaged with the back of said slide block 5. Secured upon the opposite end of said fulcrum shaft 58 is a rocking arm 61. Pivotaly mounted in connection with said frame-work or supporting structure 2 is a bell-crank lever means 62, the upper arm of which is operatively related to said rocking arm 61 by a connecting rod 63, while the lower arm is provided adjacent to its free end with laterally projecting studs 64 operatively engaged by a cam means 65 mounted on and driven by said lay shaft 45, whereby said bell-crank lever means 62 is oscillated, and consequently causes, through the oscillation of said rocking arm 61 and said lever arm 59, a timed reciprocation of said slide block 5 and cutting and forming die 6. The wire guide 12 adjacent to the cutting and forming die 6 is provided with a chamfered portion 66 against which a portion of the die 6 rides, so that the adjacent lower edge of the die 6 serves to shear or cut off the portion of wire 13 projecting from said wire guide 12 when the die 6 descends. The die 6 is also provided with an inverted U-shaped cutaway portion 67 internally grooved as at 68 in conformation to its shape. The first operation of the machine is comprised in feeding the wire 13 beneath the die 6, then cutting and forming the same into a U-shaped staple 69. As the cross-head moves upward the wire 13 is fed through the side guides 12 into position, by the means already above described. The anvil-member 31 is also

positioned in operative relation beneath the wire 13 and in line with the cutaway portion 67 of the die 6, as the cross-head 8 moves upward, as already above described. When the wire 13 is thus positioned over the anvil-member 31, the transmission mechanism for operating the die 6 performs its operative stroke, whereby the die 6 is caused to descend upon the projecting portion of wire 13, first cutting off said portion 70 from the main body thereof, and then bending the ends of said portion downward over the anvil-member 31, as the cutaway portion 67 moves downward in straddling relation to said anvil-member. The wire is thus 75 formed into a staple 69, having its legs or points directed downward, and held against displacement by the embrace of the groove 68 of said cutaway portion 67 of said die. 80

The staple being thus formed, the next 85 operation of the machine is comprised in picking up and bunching a requisite quantity of brush-bristles 70, and then carrying the same into position beneath the staple 69. The mechanical means for accomplishing these results comprise a table 71 for supporting a mass of prepared bristles 70 lying endwise in proper relation to a pick-up and bunching means. In order to move the mass of bristles into proper relation to 90 said pick-up and bunching means, as the quantity of the same is reduced by the operation of the machine, the following mechanism is provided. Mounted on said table 71 in back of the bristles 70 is a bearing member 100 72 through which pass slidale guide-rods 73. Connected with the forward end of said guide-rods is a push-plate 74 which backs up the said bristles. Connected with the rearward end of said guide-rods is a slide member 75. Secured to said slide-member 75 is a flexible cord 76, which runs forwardly to a pulley 77 mounted on said bearing member 72, over which it runs rearwardly to an idler pulley 78 mounted in a 105 bearing 79 at the outer extremity of said table, the free end of said cord bearing a suspended weight 80. The pull of this weight 80 upon the cord tends to propel said guide-rods forward with a constant 110 pressure, thus forcing the push-plate 74 to press and feed the bristles 70 constantly toward the bristle pick-up and bunching means. 115

The said bristle pick-up and bunching 120 means comprises a transverse spindle 81 mounted in bearings 82 connected with said head bracket 3, and so disposed as to be positioned on the left of said wire cutting and forming die mechanism. Loosely mounted upon the outer extremity of said spindle 81 is a segmental pick-up plate 83, provided in its marginal periphery with a properly located obliquely indented open pick-up slot 84. An adjustable plate 85 secured in slid- 125 130

able relation to said slot 84 by means of a nut and bolt fastening device 86, is adapted to be adjusted to regulate the depth of said slot 84, and consequently the amount of bristles to be picked up and bunched therein. Fixed upon said spindle 81, in back of said pick-up plate 83, is a segmental driver-plate 87, provided at its lower side, at its marginal periphery, with a pointed projection 5 which serves as a closure-member 88, and which is adapted to move across the open end of said pick-up slot 84 to close the same after the required quantity of bristles have been picked up and bunched in the latter. A coupling stud 89 projects from the rear face of said pick-up plate 83 into a coupling slot 90 provided in said driver-plate 87. Fixed upon the rearward end of said spindle 81 is a spur gear 91. Journaled upon a supporting stud 92, connected with said head bracket 3, is a segmental gear or rack 93, which meshes operatively with said spur-gear 91, the same having an arm 94 to which is pivotally secured a connecting-rod 25 95, which interconnects said gear or rack 93 operatively with the upper arm of a bell-crank lever 96 mounted in connection with said frame-work or supporting structure 2. The lower arm of said bell-crank lever 96 30 extends to a point intermediate of the lay-shaft 45 and counter shaft 48, and is provided with oppositely projecting lateral studs 97 adjacent its free end, one of said studs being operatively engaged by a down-stroke producing cam 98 which is fixed upon said lay-shaft 45, and the other of said studs being operatively engaged by an up-stroke producing cam 99 which is fixed upon said counter shaft 48, thereby oscillating 35 said bell-crank lever 96 to transmit properly timed oscillatory movements to said bristle pick-up and bunching mechanism, as will be understood from an inspection of the drawings.

45 Arranged in connection with said head bracket 3, in vertical alinement below said staple cutting and forming means and the plunger rod 10, is a bristle folding member 100 having a vertical passage therethrough.

50 Arranged within said passage, at the right side thereof, is a grooved staple guide piece 101, and at the left side thereof a similar grooved staple guide piece 102. The right staple guide-piece 101 extends upwardly to 55 abut against the end of the staple cutting and forming die 6, when the latter operates, so that it is alined ready to receive the right hand portion of the staple when the latter is fed downward, as will presently appear.

60 The bristle folding member 100 and the left staple guide-piece 102 are cut away at their upper ends to provide a passage or opening 103 through which the bristle pick-up and bunching means may pass to carry a 65 bunch of bristles beneath the staple and

ready to be embraced thereby. Before the staple and bristles are fed downward, this passage or opening 103 is closed by a gate-member 104 which is pivotally mounted by means of a spindle 105 upon the face of said guideway 4. Fixed upon the rearward end of the spindle 105 is a pulley 106 to which is secured one end of a pull-spring 107 which is anchored at its opposite end to the back of the guideway 4. The tension of said pull-spring 107 normally returns and holds said gate-member 104 lifted or in open position. The gate-member 104 has a grooved guide-face 108, which when the gate member is moved to closed position, alines itself with the left guide-piece 102 to complete the guide means for the left hand portion of the staple, when the latter is fed downward. The means for closing said gate-member 104 comprises a pin 109, which projects rearwardly from the back of said pick-up plate 83, and which when the latter swings downward, moves into an open receiving slot 110 formed in said outer periphery of the gate-member, so that after the bristles carried by the pick-up plate have moved past the end of the gate-member, the said pin will, in its movement, reach the bottom of said slot 110 and thereupon move the gate-member to closed position.

95 The operation of the bristle pick-up and bunching means and associated mechanism is as follows:—

When the pick-up plate 83 is in normal initial position its open pick-up slot 84 has 100 picked up and bunched in longitudinal arrangement a quantity of bristles 70 from the mass supported upon the table 71. The wire staple having been cut and formed, the transmission mechanism now operates to 105 impart a downward movement to said driver-plate 87. Since the pick-up plate 83 is loose on the spindle 81, the driver-plate 87 first moves forward relative to the still stationary pick-up plate 83 until the end of 110 the coupling slot 90 engages the coupling stud 89 of the latter, and in so doing first moves the closure-member 88 in closing relation to the open end of the pick-up slot 84, thereupon preventing the falling away 115 of the bunched bristles disposed in the latter, while the continued movement of said driver-plate carries downward with it said pick-up plate. The pick-up plate is thus moved to carry said bunched bristles beneath and in alinement with the previously formed staple, and in this movement the gate-member 104 is closed after the bristles carried by the pick-up plate have passed, as indicated in Fig. 4 of the drawings. When 120 the bunched bristles have thus been carried downward and positioned relative to staple, and the gate-member closed, the plunger-rod 10 is moved downward by a properly timed 125 descending movement of the cross-head 8, 130

(the anvil-member 31 having in the meantime been withdrawn). The downward movement of the plunger-rod 10 causes its end to engage the top of the staple, and 5 force the same downward between the grooved guides provided by said gate-member and left guide piece 102, and by said right guide-piece 101, in so doing causing the legs of the staple to embrace or straddle 10 the bunch of bristles and then carry downward the same therewith. By the time the legs of the staple enter between the upper end of the left guide piece 102 and right guide piece 101, and have passed the gate-member 104, the opposite oscillation of said driver-plate 87 begins which results, first in moving the closure member 88, away 15 from the pick-up slot 84 so that the bristles may pass out of the same with the embracing staple, and then when the opposite end of said coupling slot 90 engages the coupling stud 89 thereupon moving the pick-up plate 83 back to normal initial position, the 20 bristles having been carried out of the pick-up slot before the return movement of said pick-up plate begins. The continued downward movement of the plunger-rod 10 carries the staple downward between the guide pieces 101 and 102, the bristles being 25 engaged by the folding member 100 to double the same end to end, as they pass downwardly through the latter. A table 111 serves to support a suitable brush-back 112 beneath the guide-pieces and folding member, so that the plunger-rod 10 in completing 30 its descending movement, finally forces the staple free of the guides, and drives the same into the brush-back 112, thereby fastening the bristles to the brush-back 112, as 35 indicated in Fig. 1 of the drawings. The cycle of operations, thus briefly described is automatically continued, in properly timed 40 relation to each other, the operator shifting the brush-back 112 on the table 111 to determine the positioning of the bunched bristles in their fastened relation to said brush-back 112.

It will be apparent that the machine is 45 of a comparatively simple construction, and yet automatic in action, and very efficient and quick in the performance of its functions.

So far as the transmission mechanism is 50 concerned, the features thereof shown in the drawings and above described, must be deemed illustrative merely, as the same are capable of being widely modified, hence I do not limit myself merely to the use of the kind of transmission shown, but may use 55 any mechanical variation thereof found expedient.

I am aware that some changes may be 60 made in the various arrangements and combinations of the several devices and parts, as well as in the details of the construction

of the same, without departing from the scope of my invention as above described, and as defined in the following claims. Hence, I do not limit my invention to the exact arrangements and combinations of the 70 various devices and parts as described in the foregoing specification, nor do I confine myself to the exact details of the construction of the same as illustrated in the accompanying drawings. 75

I claim:

1. In a brush-making machine, an oscillatable bristle gathering and feeding means, a bristle folding means having staple guides, a normally open pivoted gate-member 80 mounted above and at one side of said folding means adapted to complete said staple guides when closed, and means for moving said gate-member into closed position after said bristle gathering and feeding means 85 have operatively positioned a bunch of bristles relative to said folding means.

2. In a brush-making machine, an oscillatable bristle gathering and feeding means, a bristle folding-member having a vertical 90 folding passage, grooved staple-guides within said folding passage, one side of said folding-member being cut away to provide a lateral passage giving the bristles carried by said gathering and feeding means access 95 into alignment with said folding passage, a pivoted gate-member mounted adjacent to said folding-member for closing said lateral passage thereof, said gate-member having a grooved channel adapted to align itself with 100 a staple-guide of said folding-member to complete the same, and means for moving said gate-member into closed position after the bristles carried by said gathering and feeding means have passed through said lateral passage. 105

3. In a brush-making machine, an oscillatable bristle gathering and feeding means, a bristle folding-member having a vertical 110 folding passage, grooved staple-guides within said folding passage, one side of said folding-member being cut away to provide a lateral passage giving the bristles carried by said gathering and feeding means access into alignment with said folding passage, a pivoted gate-member mounted adjacent to 115 said folding-member for closing said lateral passage thereof, said gate-member being also positioned adjacent to the path of movement of said bristle gathering and feeding means, 120 said gate-member having a grooved channel adapted to align itself with a staple-guide of said folding-member to complete the same, spring means for returning the same to and maintaining the same in normal open position, and means on said bristle gathering and feeding means adapted during the feeding movement of the latter to engage and close said gate-member after the bristles 125 have passed through said lateral passage to 130

operative position relative to said folding-member.

4. In a brush-making machine, an oscillatable pick-up plate having an open oblique 5 pick-up slot in its periphery for gathering up a bunch of bristles from a main supply thereof, a spindle upon which said pick-up plate is loosely mounted, a driver-plate fixed on said spindle, a pointed projection at one 10 end of said driver-plate for closing said pick-up slot during the feeding movement of said pick-up plate, means coupling said driver-plate in driving relation to said pick-up plate, said coupling means being adapted 15 to permit a preliminary limited movement of said driver-plate in advance of said pick-up plate to position said pointed projection in closed or open relation to said pick-up slot, transmission means for oscillating said 20 spindle, a bristle folding means having staple-guides, a normally open pivoted gate-member mounted at one side of said folding means and adjacent to the path of movement of said pick-up plate, said gate-member being 25 adapted to complete said staple guides when closed, spring means associated with said gate-member for returning the same to and maintaining the same in normal open position, and a stud projecting from said 30 pick-up plate adapted during the feeding movement of the latter to engage and close said gate-member after the bristles have

been operatively positioned relative to said folding means.

5. In a brush-making machine, a bristle 35 gathering and feeding means comprising an oscillatable pick-up plate having an open oblique pick-up slot in its periphery for gathering up a bunch of bristles from a main supply thereof, a spindle upon which 40 said pick-up plate is loosely mounted, a driver-plate fixed on said spindle, a pointed projection at one end of said driver-plate for closing said pick-up slot during the feeding movement of said pick-up plate, a coupling stud projecting from the body of said pick-up plate, said driver-plate having a concentric coupling slot into which said coupling stud enters so as to permit of an initial 45 limited movement of said driver-plate before movement is imparted to said pick-up plate to permit a prior positioning of said pointed projection in operative relation to said pick-up slot, and transmission means for producing a properly timed driving 50 oscillation of said spindle.

In testimony, that I claim the invention set forth above I have hereunto set my hand this 4th day of June, 1918.

JOHN D. GLADWIN.
